H. KLOH

SAFETY BUTTON HOOK

Filed July 2, 1926

Inventor

H. Kloh.

By

John P. Duane

Attorney

UNITED STATES PATENT OFFICE.

HERMAN KLOH, OF TRIMBLE, OHIO, ASSIGNOR OF ONE-HALF TO GEORGE W. ROSE,
OF GLOUSTER, OHIO.

SAFETY BUTTONHOOK.

Application filed July 2, 1926. Serial No. 120,128.

This invention relates to new and useful improvements in safety button hooks, and has for its principal object to provide a simple and practical device of this character which may be advantageously used in fastening shirt collars, coat collars, or other wearing apparel in place.

The device consists in the novel features of construction, combination, and arrangement of parts illustrated in the accompanying drawings and more particularly pointed out in the appended claim.

In the accompanying drawings, which are for illustrative purposes only and are therefore not drawn to scale:

Figure 1 is a plan view of a safety button hook constructed in accordance with my invention.

Figure 2 is a reverse plan view.

Figure 3 is an enlarged central longitudinal section, taken on line 3—3 of Figure 1.

Figure 4 is a vertical longitudinal section, taken on line 4—4 of Figure 3.

Figure 5 is an edge view of a modified form of my invention and Figure 6 is an enlarged central longitudinal section.

The other views are plan views of different modifications of my invention.

Referring to the drawings for a more particular description of my invention and in which drawings like parts are designated by like characters throughout the several views, my device comprises two corresponding circular heads which are spaced a suitable distance apart and connected together by the elastic cord or link 2.

In carrying out my invention, the elastic cord or link is provided at each end with a wire hook 3 and in connecting the ends of the elastic cord or link with the heads 1 the outer ends of the wire hooks 3 are first inserted through corresponding transverse openings 4 formed adjacent to the outer edges of the disc plates 5 and then bent inwardly back upon themselves for suitable engagement with the shirt collar or other garment. The disc plates 5 fit within the circular outer members 6 whose edges 7 are bent or crimped over the edges of the disc plates in order to securely retain the latter in place. If desired, packing discs 8 of card board or other suitable material may be arranged between the inner walls or faces

of the disc plates and outer members 6 and said packing discs may be formed with transverse slots or recesses 9 to receive the inner ends of the elastic cord in order that the inner faces of the disc plates will fit snugly against the packing discs. It is to be understood, however, that I do not necessarily use the packing discs and may form the heads 1 merely of the disc plates and outer members. It will be noted that the flange 10 of each outer member 6 is provided with a transverse slot or recess 11 to accommodate the corresponding end of the elastic cord or link 2.

The heads 1 are not necessarily of circular form but may be made elongated, as illustrated in Figure 3, or any other desired shape or form. In the modified form shown in Figure 3 the head is merely made in one piece in the form of a singular strip whose ends 12 are bent inwardly and brought together and in this construction or form of my device the ends of the elastic cord or link 2 extends through the openings in the inner ends of the heads and fit between the inner and outer sections or members 13 and 14, respectively, of the latter.

From the foregoing description taken in connection with the drawings it is thought that the construction, operation, and advantages of my invention will be readily understood without requiring a more extended explanation.

Having described my invention, what I claim as new and desire to secure by Letters Patent, is:

In a device of the character specified, a pair of corresponding spaced heads, each consisting of a disc plate formed with a transverse opening, an outer circular member or casing having one edge bent or crimped over the edge of the disc plate, a packing disc between the inner walls of the disc plate, and casing, respectively, an elastic cord and wire hooks connected with the ends of the elastic cord or link and extending through the transverse openings of the disc plates, said packing discs formed with transverse recesses to receive the inner ends of the elastic cord.

In testimony whereof I affix my signature.

HERMAN KLOH.
